(57) **CLAIM**

The ornamental design for sterilization apparatus, as shown and described.

DESCRIPTION

FIG. 1 is a perspective view of the sterilization apparatus;
FIG. 2 is a rear view of the sterilization apparatus;
FIG. 3 is front view of the sterilization apparatus;
FIG. 4 is a left side elevational view of the sterilization apparatus;
FIG. 5 is a right side elevational view of the sterilization apparatus;
FIG. 6 is a bottom plan view of the sterilization apparatus;
and,
FIG. 7 is a top plan view of the sterilization apparatus.
